UNITED STATES PATENT OFFICE

CHARLES L'ENFANT, OF NEW YORK, N. Y.

BILL FOLD

Application filed November 26, 1927. Serial No. 235,814.

This invention relates to billfolds or similar foldable article-receiving cases, and has for its general object and purpose to provide an article of this character of simple and novel construction, enabling the same to be expeditiously produced in large quantities with an economical consumption of materials, and at comparatively low manufacturing cost.

It is a more particular object of my present improvements to provide such a billfold having a longitudinally extending bill receiving pocket in addition to a plurality of card receiving pockets and wherein the several parts are so constructed and relatively arranged as to also enable a check book to be conveniently carried in the bill receiving pocket and the device folded upon itself along a central transverse line and the sections thereof fastened in such folded relation so that in such compact folded form, the billfold will not be excessively bulky and can be conveniently carried in the pocket.

In a preferred embodiment of my invention, the device consists essentially of inner and outer main sections, and it is one of the important features of the invention to provide said inner section with a main body wall cut from a single piece of cloth, imitation leather or other material and embodying a plurality of relatively foldable parts to thereby produce the inner longitudinal wall of the bill receiving pocket and a plurality of card receiving pockets on the outer face of said wall.

It is also another object of the invention to provide an outer section of the billfold of novel construction, whereby the inner section thereof with the parts in properly folded relation may be accurately superimposed upon the inner side of said outer section and interlocked therewith so that the marginal edges of the outer section may be turned inwardly upon the marginal edges of the said inner section and stitched or otherwise permanently secured thereto.

It is also an additional object of the invention to provide an accessory attachment for the billfold, a number of additional card receiving pockets having transparent windows hingedly secured to an attaching mem-

ber along the transverse central line thereof, the opposite end portions of which member are adapted to be removably engaged in the opposed ends of card receiving pockets on the inner section of the billfold.

With the above and other objects in view, the invention consists in the improved billfold, and in the form, construction and relative arrangement of its several parts, as will be hereinafter more fully described, illustrated in the accompanying drawings, and subsequently incorporated in the subjoined claims.

In the drawings, wherein I have illustrated several simple and practical embodiments of my present improvements, and in which similar reference characters designate corresponding parts throughout the several views,—

Figure 1 is a plan view of the blank from which the inner section of the billfold is formed;

Fig. 2 is a similar view showing another stage in the method of making said inner section of the billfold;

Fig. 3 is a perspective view showing a succeeding step in making said inner section;

Fig. 4 is a perspective view of the outer section of the billfold;

Fig. 5 is a similar view showing the inner section as seen in Fig. 3 assembled upon said outer section in position to be permanently secured thereto;

Fig. 6 is an inner face view of the completed billfold;

Fig. 7 is a perspective view of the billfold folded upon itself and the parts fastened to each other;

Fig. 8 is a plan view of the inner section of a billfold showing a slightly modified construction;

Figs. 9 and 10 are perspective views illustrating further steps in making this inner section of the modified form of the device;

Fig. 11 is a view similar to Fig. 5 showing the inner and outer sections assembled;

Fig. 12 is an inner face view of the completed billfold;

Fig. 13 is a detail side elevation illustrat-

ing the auxiliary transparent card holders for the billfold;

Fig. 14 is a perspective view of the billfold open showing the card holders in place and illustrating another way in which a check book may be associated therewith, and

Fig. 15 is a perspective view of the device when folded.

Referring now in detail to Figs. 1 to 7 inclusive, of the drawings, the embodiment of my invention as therein shown is composed of two principal sections, namely, the inner section illustrated in Figs. 1 and 3 of the drawings and the outer section shown 15 in Fig. 4.

The inner section consists essentially of a one piece body wall of cloth, imitation leather, or other suitable material indicated at 5 which is cut in proper outline form or 20 shape to produce the several relatively foldable walls or parts as will be presently described.

Prior to the cutting of this flexible material, there is secured upon the inner or wrong side thereof by a suitable adhesive, a stiffening sheet of cardboard, heavy linen or other suitable reinforcing material, the said sheet of reinforcing material being weakened or scored along the lines indicated at 7 so that 25 the section of the reinforcing material between these parallel score lines may be readily removed. The reinforced sheet is stamped or cut out to provide the pocket forming walls 8 and 9 respectively, on opposite sides

35 of its center and in line with each other, and also to provide the additional pocket forming walls 10 opposite to the walls 8. These different parts of the blank are adapted to be folded relative to each other along 40 the lines indicated at 11, and if desired in order to facilitate this folding, the cardboard reinforcing material 6 may be scored along these lines. The inner opposed edges 7 of the walls 8 are indented or cut out as shown 45 at 12, the purpose of which will be evident from reference to Fig. 6 of the drawings.

The blank also includes a widened extension 13 of one of the pocket walls 9. The leather or other facing material 5 extends 50 beyond the ends of the walls 9 and the extension 13 and is adapted to be folded inwardly thereupon and secured to the same by a suitable adhesive as indicated at 14 so as to provide these parts with finished end edges.

55 One of the pocket walls 10 is provided with a flap extension 15 at one of its ends foldable along the line 16, and adjacent to this fold line, a transversely extending slot 17 is cut through said flap in order to facilitate the folding thereof, together with the parts with which said flap is subsequently connected.

60 The facing material 5 between the edges 7 of the pocket walls 10 and at the fold line 11 between said walls and the pocket walls

8 is provided with a short free extension 18 which is adapted to be folded over upon the inner side of the facing sheet as will be seen in Fig. 2 of the drawings to provide a finished edge to the facing material between these 70 opposed edges of the pocket walls.

After the reinforced blank has been cut out in the manner above described, the part or extension 13 of the pocket wall 9 is cut off from said pocket wall along one edge of the latter as indicated at A. Upon referring now to Fig. 2 of the drawings, it will be observed that this cut off portion 13 of the blank is then reversed in position and arranged upon the inner side of the facing sheet 5 between the 75 pocket walls 10 so as to bridge the space between said pocket walls and extend upon the same. The finished edge formed by turning over the facing material at 14 is accurately located in line with the finished edge of the facing sheet 5 formed by turning the extension 18 thereof inwardly upon said sheet, the part 13 overlying this inwardly turned extension of the facing sheet. The opposite edge of the part 13 is spaced above the lower 80 edges of the pocket walls 10 and said part 13 is then suitably secured to the facing sheet 5, as by the central transverse line of stitching 19. The lower edge of the material 5 is also cut away between the edges 7 of the 85 pocket walls and is in line with the edge of the part 13. At each side of this line of stitching, the part 13 remains free or unsecured.

In the next step the pocket forming walls 9 of the blank are folded over and inwardly along the lines 11 upon the walls 8, said walls 8 and 9 being of equal length so that the free ends of the walls 9 will overlie the indented or recessed end edges 12 of the walls 8. These 100 two walls 8 and 9 at each side of the center of the blank are then folded together over and upon the walls 10 and upon the end portions of the part 13 as will be clearly seen from reference to Fig. 3 of the drawings, said walls 105 8, 9 and 10 all being of uniform width so that when thus folded, their free longitudinal edges lie in the same plane. It will therefore, be seen that there is thus produced two pockets between the walls 8 and 9 open at 110 their opposed inner ends, and also two additional pockets between the walls 9 and 10 which are open at both of their ends and into the inner opposed ends of which the free portions of the part 13 extend.

115 The outer section of the device consists of inner and outer sheets of leather or other flexible material indicated at 20 and 21 respectively. The inner sheet 20 is preferably reinforced on the face thereof opposed to the outer sheet 21 by a long strip or sheet of paper or cardboard indicated at 22 and a relatively 120 short length of paper or cardboard 23 secured to one end of said flexible sheet in 125 spaced relation to the reinforcing material 130

22. These reinforcing sheets 22 and 23 are also somewhat narrower than the leather or fabric sheet 20 which projects at one of its longitudinal edges beyond the reinforcing sheets as indicated at 24. The other longitudinal edges of the inner leather or fabric sheet 20 and its reinforcing sheets are secured to one longitudinal edge of the outer leather sheet 21, preferably by turning over the edge of this outer sheet and stitching the parts together as indicated at 25. By means of this same line of stitching, the relatively wide end portion 26' of an additional part 26 is secured along its longitudinal edges to the inner and outer sheets 20 and 21, the other narrow end portion 26^a of said part 26 remaining free or unattached and extending inwardly over the sheet 20. This part 26 also preferably consists of a sheet of cardboard having its inner side faced with imitation leather.

It will also be noted that the outer leather sheet 21 is of greater length and width than the inner sheet 20 so that after the parts have been secured together by the stitching 25, the opposite longitudinal margin and the end marginal portions 27 of the outer sheet 21 project beyond the corresponding end edges of the inner sheet 20.

Having assembled the several parts composing the outer section of the device in the manner above described and also having one of the inner sections constructed and folded in the manner shown in Fig. 3 of the drawings, the said inner section is now arranged in superimposed relation upon the inner side of said outer section, and the flap extension 15 of the pocket wall 9 of said inner section is inserted between the widened end portion 26' of the part 26 and the inner sheet 22 of said outer section while the narrow portion 26^a of said part extends longitudinally between the wall 10 and the opposed pocket wall 9 of the inner section of the device. This arrangement will position the integrally connected edges of the pocket walls 8 and 9 along the fold line 11 substantially in coincident parallel relation with the line of stitching 25, and slightly below the longitudinal edge of the outer section of the device. Also when thus positioned, the slot 27 in the flap 15 approximately overlies the unreinforced portion of the inner sheet 20 of said outer section between the ends of the reinforcing parts 22 and 23 thereof.

The projecting marginal edge portions 27 of the sheet 21 of the outer section are now turned inwardly over and upon the free longitudinal edges of the walls 8, 9 and 10 of the inner section and similarly over the end of the flap 15 and part 26' at one end of the device and over the end of the walls 8, 9 and 10 at the other end of the device, said in-turned marginal edges and the several parts which

they overlap being then secured together by the stitching lines shown at 28. It will however, be observed that the lower end edge of the part 13 is not overlapped by the inturned marginal edge of the outer sheet 21 and is not secured by the stitching 28. The part 26 and flap 15, together with the inner and outer sheets 20 and 21 of the outer section may then be folded inwardly along the slot 17 to provide the fastening flap indicated at 29 in Fig. 6 of the drawings. This flap is provided with one element 30 of a common form of snap fastener while the other element thereof indicated at 31 is suitably secured to the outer section of the device along its longitudinal center line and adjacent its opposite end. Thus, when the body of the billfold is folded upon itself along its central transverse line, the flap 29 may be folded over upon the other end of the billfold and the fastening elements 30 and 31 connected.

It will be evident that owing to the great economy effected in the use of materials by the above described construction of the inner and outer sections of the device and the manner of and assemblage and connection with each other, the device when folded as in Fig. 6 will be of unusually compact form and minimum bulk. Furthermore, I have found that by reason of such construction, it is possible to carry a foldable check book as indicated at 32 in the longitudinal pocket formed between the inner sheet 20 of the outer section of the device and the walls 10 of the inner section thereof, in addition to the bills contained therein and to then fold the device as seen in Fig. 6 of the drawings without serious inconvenience in the use of the device to the increased bulk thereof. In addition to the bill and check book holding pocket, it is seen that the device also provides in the inner section thereof two opposed pockets open at their inner ends to receive cards, memoranda or other articles, and also an additional pocket at one end of said inner section between the walls 9 and 10 which is open at its inner end and closed at its outer end. If desired, instead of placing the check book within the longitudinal bill receiving pocket, the stub end of the cardboard backing sheet for the checks may be inserted between the other pocket forming walls 9 and 10 of the device adjacent to the flap extension 29 as seen in Fig. 14 of the drawings. It will thus be appreciated that I have succeeded in producing a billfold, which while of exceedingly simple construction and capable of rapid manufacture, possesses relatively great carrying capacity and greater utility than articles of this kind as heretofore made. The provision of the part 13 and the central portion of the facing sheet 5 of the inner section of the device which is unsecured to the outer section, permits of the distention of said inner facing

120

125

130

sheet without buckling, the ends of the bridging piece 13 sliding freely between the walls 9 and 10. This feature however, is not herein claimed, as it forms the subject matter of my Patent No. 1,680,687, granted August 14, 1928.

In Figs. 9 to 14 of the drawings, I have shown a slightly different form of the device wherein the reinforced blank of the inner section is provided with the pocket walls 8' and 10', the fabric facing of the walls 8' at their opposed ends having projecting portions indicated at 8^a to which the separate pocket walls 9' are attached at one of their ends by 15 a suitable adhesive. The outer end edges of the pocket walls 8' in this case are indented or recessed as at 12'. The fabric facing sheet is extended beyond the outer end of one of the walls 10' and a separate reinforcing piece 20 of cardboard or paper 15' is secured thereto to form a foldable flap. The outer end of the other pocket wall 10' is also formed with a foldable flap or extension 10^a, and as seen in Fig. 10 of the drawings, this flap is adapted 25 to be positioned between the walls 8' and 9' within the open end of the pocket formed thereby. The part 13' is applied in the same manner as above described, and in this case the longitudinal edge of the facing material 30 projects beyond the longitudinal edge of the stiffening or reinforcing material as shown at 5'. In this construction, an outer section identically the same as that above described is provided and the inner section is assembled 35 therewith in the same manner, namely, the flap 15' is interlocked with the part 26 and the lower longitudinal marginal edge and the end edges of the sheet 21 of the outer section is then turned inwardly and secured to the 40 corresponding edges of the parts of the inner section. One element of the snap fastener is secured through the flap 10^a and the walls 9' and 10' of the inner section.

In this alternative embodiment of my invention, it will be seen that there is provided the longitudinal bill receiving pocket and the two pockets of the inner part or section of the billfold, which however, in this case are closed at their inner ends and open at their 50 outer ends, and there is also provided the additional pocket in one end portion of the device between the walls 9' and 10'.

In either form of my improved billfold as above described, I may employ an accessory 55 consisting of a plurality of duplex card holding members indicated at 33 each having transparent side walls of celluloid or other similar material. As shown at Fig. 13, these members are centrally secured by a transverse 60 line of stitching 34 to a reinforced fabric part 35, said part projecting longitudinally in opposite directions from said line of stitching. These end portions of the member 35 may be flexed or bent sufficiently to permit 65 the same to be inserted between the pocket

walls 9 and 10 or 9' and 10' at the inner ends thereof, thus retaining the card holding attachment in place with the fold line 34 thereof in substantial registration with the fold line 19 of the billfold. Therefore, there may 70 be conveniently combined in the one article, any desired number of the holders 35 for lodge cards, licenses or the like, together with the check book and the additional pockets of the inner section to receive visiting cards, 75 memoranda, etc. Nevertheless, when the device is folded and fastened as shown in Fig. 15 of the drawings, the parts are compactly held so that the bulk thereof is reduced to a 80 minimum.

From the foregoing description considered in connection with the accompanying drawings, the several illustrated embodiments of my present improvements will be clearly and fully understood. It will be seen that I have devised an exceedingly simple construction of the several parts and a method of assembling the same and securing said parts in proper relative position which enables such articles to be manufactured on a quantity 90 production basis at a minimum cost in labor and materials, so that notwithstanding the numerous features of utility which such a device possesses, it may be profitably sold at a price not exceeding that of such articles 95 as heretofore produced in this art. Of course, it is apparent that the novel features of my present disclosure might also be embodied in various other sizes and in other forms or shapes than that shown in the drawings, and that various materials, used in the manufacture thereof and metal trimming of gold, silver or other precious metal also utilized, in accordance with the quality of the article and the price at which the same is to be sold. 100

It is accordingly to be understood that in the commercial manufacture of a billfold embodying the essential features of my present improvements, I do not desire to be restricted to the precise form, construction and relative arrangement of the several elements as herein disclosed, but reserve the privilege of resorting to all such legitimate changes as may be fairly embodied within the spirit and scope of the invention as claimed. 110

I claim:

1. A billfold comprising inner and outer elongated sections forming a bill receiving pocket, said sections at one of their ends having interlocking parts for retaining said inner section in predetermined superimposed relation upon said outer section, and said outer section including a facing sheet having marginal edge portions folded inwardly upon and secured to the corresponding marginal edges of said inner section. 120

2. A billfold comprising inner and outer sections forming a bill receiving pocket open along one longitudinal edge of the billfold, said inner section including integrally con- 130

5 nected folded parts forming additional pockets open at one of their ends, said inner section adapted to be positioned in superimposed relation upon said outer section and said outer section including an outer facing sheet having marginal edge portions inwardly turned upon the corresponding edges of said inner section and upon the walls of said latter pockets, and stitched thereto to secure 10 said marginal edges of the inner and outer sections together and close said pockets along one of their side edges.

15 3. A billfold comprising inner and outer sections forming a bill receiving pocket open along one longitudinal edge of the billfold, said inner section consisting of a single reinforced blank of flexible material having portions folded relative to each other to form additional pockets open at one of their ends, said 20 inner section arranged in superimposed relation upon said outer section and the outer section including a facing sheet having marginal edge portions inwardly turned upon and secured to the corresponding marginal edges 25 of said inner section and closing the pockets of the latter section along one of their side edges.

30 4. A billfold comprising inner and outer sections having a bill receiving pocket open along one longitudinal edge of the billfold, said inner section consisting of a single reinforced blank of flexible material having parts folded relative to each other to provide the inner wall of said bill receiving pocket, and 35 additional pockets on said inner wall open at one of their ends, said inner wall having a foldable flap extension at one of its ends, a foldable member extending longitudinally upon one end of said outer section and on the 40 inner side thereof and attached along a portion of one of its side edges to the edge of said outer section, said member having a free inner end portion, said flap extension of the inner section adapted for insertion between 45 said member and the wall of the outer section to position said sections in superimposed relation to each other, and said outer section including a facing sheet having marginal edge portions turned inwardly upon and secured to 50 the corresponding edges of the folded parts of said inner section.

55 5. A billfold comprising inner and outer sections forming a bill receiving pocket open along one longitudinal edge of the billfold, said inner section consisting of a single blank of flexible material, reinforcing sheets secured to one side of said material and foldable therewith to provide an inner wall for the bill receiving pocket and additional pockets on 60 said wall open at one of their ends, said reinforced pocket walls terminating at opposite sides of the center of said inner wall of the bill receiving pocket, a foldable bridging sheet secured along a central transverse line 65 to the flexible material of said inner wall and

projecting in opposite directions therefrom between said additional pockets on said wall and the outer side of the wall, and said outer section having marginal edge portions inwardly turned upon and secured to the corresponding edges of the folded parts of said inner section. 70

6. A billfold comprising inner and outer sections forming a bill receiving pocket open along one longitudinal edge of the billfold, 75 said inner section consisting of a single blank of flexible material having reinforced folded parts forming the inner wall of said bill receiving pockets, and additional pockets on said inner wall open at one of their ends and spaced upon opposite sides of the center of said wall, a bridging member centrally secured along a transverse line to the unreinforced central part of said inner wall and extending therefrom in opposite directions between the reinforced parts of said wall and the additional pockets thereon, said outer section and the wall of said inner section having interlocking means at one of their ends for positioning said sections in superimposed predetermined relation and said outer section including a facing sheet having marginal edge portions inwardly turned upon and secured to the corresponding edge portions of 80 said inner section. 85

90 7. A billfold comprising inner and outer sections forming a bill receiving pocket open along one longitudinal edge of the billfold, 95 said inner section consisting of a single blank of flexible material having reinforced folded parts forming the inner wall of said bill receiving pockets, and additional pockets on said inner wall open at one of their ends and spaced upon opposite sides of the center of said wall, a bridging member centrally secured along a transverse line to the unreinforced central part of said inner wall and extending therefrom in opposite directions between the reinforced parts of said wall and the additional pockets thereon, said outer 100 section including a facing sheet and a lining sheet secured together along one of their longitudinal edges, a main reinforcing sheet secured upon one side of said lining sheet and a second reinforcing sheet secured to the lining sheet at one end thereof and in spaced 105 relation to said main reinforcing sheet, the wall of said inner section having a flap extension at one of its ends and a transverse slot at the inner end of the flap extension, means secured to one end of said outer section interlocking with said flap to position the slot in the wall of said inner section in registering relation with the space between said reinforcements on the lining sheet of the outer section whereby said flap with the end of the outer section may be easily folded, and the facing sheet of said outer section having marginal edge portions inwardly turned upon 110 115

120 125

130

125

130

130

and secured to the corresponding marginal edge portions of said outer sections.

8. A billfold comprising separate unit sections each having a flap forming end portion including parts mutually interlocking with each other when said sections are arranged in superimposed relation to form a bill-receiving pocket therebetween, said superimposed sections adapted to be folded along a transverse line in closing the billfold, and means for securing said sections to each other along one of their longitudinal edges and their opposite end edges.

9. A billfold comprising inner and outer separate unit sections, the inner section including folded parts providing a plurality of pockets, each of said sections at one of their ends having flap forming portions including parts mutually interlocking with each other to retain said sections in predetermined superimposed relation, and means for securing said sections together along their opposite end edges and one of their longitudinal edges, the said means also closing the latter side edges of the pockets of said inner section, said sections forming a bill-receiving pocket therebetween open at the opposite longitudinal edge of the billfold.

In testimony that I claim the foregoing as my invention, I have signed my name hereto.

CHARLES L'ENFANT.
